SPRING FRAME SEAT

Felix J. Trainor, Newcastle, Ind., assignor to
 Trainor National Spring Company, Newcastle,
 Ind., a corporation of Indiana

Application March 8, 1935, Serial No. 9,958

5 Claims. (Cl. 155—50)

This invention relates to the art of furniture and particularly to a novel type of chair or the like wherein all of the supporting members are formed of spring material to produce a yielding, flexible structure fitting itself to the occupant with a suitable degree of resiliency and providing the utmost comfort. Another advantage of my invention is that it may be incorporated in a number of designs giving a very pleasing and striking effect suitable to be made up in varying colors and patterns. A further advantage is found in the fact that by reason of the all-metallic supporting structure, the piece of furniture is extremely durable and may even be subjected to out-of-door use without appreciable damage.

These and other objects and advantages of my invention will become apparent to those versed in the art in the following description which is made in reference to the accompanying drawing, 20 wherein

Fig. 1 is a front perspective view of a chair embodying my invention;

Fig. 2, a similar view of a slightly modified form;

Fig. 3, also a similar view of a still further modified form, and

Fig. 4, a side elevation of the form as indicated in Fig. 1.

Like characters of reference indicate like parts throughout the several views in the drawing.

Referring first to that form shown in Figs. 1 and 4, I employ a pair of runners 10 and 11, each having a major length thereof normally horizontally disposed. To these runners 10 and 11 as foundation members, I secure members generally designated by the numerals 12 and 13 symmetrical one with the other so that the description of one will be a description of the other. Taking the member 12, this member is formed of spring steel 40 to be secured by its lower forward end to the runner 11 near its forward end by any suitable means, one such means being as by a rivet 14. From this attachment with the runner 11, the member 12 curves upwardly around and rearwardly to form 45 the bend 15 and thence sweeps upwardly and rearwardly to form the rear turned longer bend 16 from which the steel slopes upwardly and thence forwardly with a rather long sweep and then is turned around upwardly and rearwardly to form the bend 17 as a forward part of an arm rest 18 produced by the steel extending rearwardly from the bend 17. From this arm rear portion 18, the steel is then carried around and upwardly to form the rear bend 19 from which 50 bend the steel then is carried upwardly to the desired height to form a back supporting end 20.

From under the arm rest part 18, another part of the member 12, designated by the numeral 21, is attached and carried around rearwardly and downwardly and thence sloped upwardly over the runner 11 into that part of the member 12 secured toward the forward end of the runner 11 so that only a relatively small part of that rear part 21 is in normal contact with the runner 11. A tie bar 22 is secured to the two members 12 and 13 just back of the attachment of those members to the runners thereunder.

Another tie bar 23 is fixed between those side members 12 and 13 on the forward legs thereof and below the curves 17 as indicated in the drawing. Also the upper ends of the back supports 20 are tied together by a bar 24, in the form herein shown as by having the bar engaged in eyes formed in the top ends of those supports 20. A seat 25 is rockably secured over the bar 23 and 20 extends rearwardly between the members 12 and 13 to have its rear end hingedly connected along the lower end of a back 26 which is hung by its top end from the bar 24. The seat 25 and back 26 may be of any usual rigid structure with resilient 25 upholstery thereover so that the distance between the bar 23 and the rear hinge line of the seat 25 with the back 26 is maintained under load.

Now when the seat or chair thus described is occupied, it will assume some such position as indicated by the dash lines in Fig. 4, depending, of course, upon the weight of the occupant and to what degree the occupant desires to rock. It is to be considered that the dash line position is merely illustrative and is not to be considered as the absolute position the various members will assume. When the occupant sits down and leans back against the back 26, the side members 12 and 13 will tend to roll back along their runners while at the same time the portions 16 and 21 40 will assume sharper curves thereby permitting a slight lowering of the seat 25 as indicated. Also the back supports 20 will permit a slight flexing rearwardly thereof so as to permit the back to assume a more inclined position. The hinging of 45 the seat and back permits easily assumed new positions as indicated so that the seat and back will readily accommodate themselves to the occupant's position. As the members 12 and 13 are thus deformed under load, the forward ends of 50 the runners 10 and 11 will tend to be lifted upwardly as indicated in Fig. 4 and the rear portions 21 of those side members will tend to roll back rearwardly on the runners as the forward ends 55 tend to lift. Thus every supporting member out-

side of the seat and back may be flexed and deformed somewhat to accommodate itself readily to the load and to permit an easy rocking of the chair. As a matter of finish and to prevent damage to the floor, the forward ends of the runners 10 and 11 are preferably turned upwardly somewhat on the curves 15 and the rear ends are provided with turned up or rolled over ends.

In the form of the invention shown in Fig. 2, 10 the supporting structure remains exactly the same as that described above with the exception that the seat 25 and back 26 are replaced with a length of fabric 27 hung between the bar 23 and the bar 24. Also for the sake of changed appearance, additional blocks 28 are placed on top of the arm rest portions 18.

In the form shown in Fig. 3, the same supporting side members are employed as before and a combined canvas seat and back 29 is employed, 20 in this case having the addition thereto of an upholstered head rest 30 and a seat cushion 31. Another modification from that shown in the two forms previously described is that on the runners 10 and 11 I add a superimposed plate 32 in each 25 case to have the rear end of that plate 32 curved upwardly near the rear end away from the runner and thence sharply downwardly to join with and be secured to the runner at its rear end. This plate is thus added to provide an increasing 30 resistance to the rocking back of the side members 12 and 13 as their portions 21 roll into contact therewith. Of course, the runners 10 and 11 may be omitted entirely in this form if desired, so that 35 the bearing plates 32 then carry the members 12 and 13 alone.

In any of the forms above described, I achieve an extremely comfortable chair which will settle back to accommodate the occupant without any 40 tendency to pitch him forward. The curves of the various members are so positioned and placed as indicated as to prevent such pitching and at the same time prevent too much freedom of the spring members.

While I have herein shown and described my 45 invention in the forms as now best known to me, it is obvious that structural changes may be made without departing from the spirit of the invention, and I, therefore do not desire to be limited to those precise forms beyond the limitations as 50 may be imposed by the following claims.

I claim:

1. In a resilient seat supporting structure, a pair of resilient runners normally horizontally disposed; a pair of resilient side members carried on said runners, each of said side members having a rearwardly bowed front leg, a rearwardly bowed rear leg sloped forwardly by its underside over its respective runner to be normally in contact with the runner over a forward portion only thereof, the upper ends of said legs being curved around toward each other to form a resilient tie therebetween; a resilient back support member extending from said tie and turned upwardly; a seat bar interconnecting said front legs; a back bar interconnecting said back support members; and a seat carried by said two bars.

2. In a resilient seat supporting structure, a pair of resilient runners normally horizontally

disposed; a pair of resilient side members carried on said runners, each of said side members having a rearwardly bowed front leg, a rearwardly bowed rear leg sloped forwardly by its underside over its respective runner to be normally in contact with the runner over a forward portion only thereof, the upper ends of said legs being curved around toward each other to form a resilient tie therebetween; a resilient back support member extending from said tie and turned upwardly; a seat bar interconnecting said front legs; a back bar interconnecting said back support members; and a seat carried by said two bars, said seat being hinged forwardly to said seat bar; and a back suspended from said back bar, said seat being hinged rearwardly to the lower end of said back.

3. A seat comprising a pair of resilient base runners; a side member fixed to each runner having a resilient front leg fixed to the forward portion of its runner curving upwardly therefrom and bowing rearwardly in a major central portion and thence curving around rearwardly to form an arm rest, said member having a rear leg fixed to said runner forward portion and sloping upwardly therefrom over the runner in increasing spaced relation and bowing rearwardly by a major central portion and thence curving around forwardly to join with said arm rest; a resilient back bar extending upwardly from said arm rest; and a seat swung between said side members.

4. A seat comprising a pair of resilient base runners; a side member fixed to each runner having a resilient front leg fixed to the forward portion of its runner curving upwardly therefrom and bowing rearwardly in a major central portion and thence curving around rearwardly to form an arm rest, said member having a rear leg fixed to said runner forward portion and sloping upwardly therefrom over the runner in increasing spaced relation and bowing rearwardly by a major central portion and thence curving around forwardly to join with said arm rest; a resilient back bar extending upwardly from said arm rest; and a seat swung between said side members, a seat carrying bar carried by said front legs below said arm rest; and a back bar carried between said back bars above said arm rest.

5. A seat comprising a pair of resilient base runners; a side member fixed to each runner having a resilient front leg fixed to the forward portion of its runner curving upwardly therefrom and bowing rearwardly in a major central portion and thence curving around rearwardly to form an arm rest, said member having a rear leg fixed to said runner forward portion and sloping upwardly therefrom over the runner in increasing spaced relation and bowing rearwardly by a major central portion and thence curving around forwardly to join with said arm rest; a resilient back bar extending upwardly from said arm rest; and a seat swung between said side members, a seat carrying bar carried by said front legs below said arm rest; and a back bar carried between said back bars above said arm rest, said seat bar being attached to said front legs on the upper portions of said rearward bowed parts.

FELIX J. TRAINOR.
